Primary Examiner — Caron D Veynar*Assistant Examiner* — Katrina N Gonzalez(74) *Attorney, Agent, or Firm* — Gerard J. McGowan, Jr.(57) **CLAIM**

The ornamental design of a bottle, as shown and described.

DESCRIPTION

FIG. 1 is a front perspective view from above of a bottle showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines are shown for the purpose of illustrating a portion of the bottle that forms no part of the claimed design.
